DISPLAY ELEMENT FOR FORMING INDICIA IN A SIGN

Donald Winrow, Weston, Ontario, Canada, assignor to
Ferranti-Packard Limited

Filed June 20, 1974, Ser. No. 481,151

Term of patent 14 years

Int. Cl. D20—03

U.S. Cl. D96—12 K

FIG. 1

FIG. 2

FIG. 3

FIG. 1 is a front perspective view of a display element for forming indicia in a sign showing my new design;

FIG. 2 is a front perspective view thereof wherein the rotatably mounted center element is in the opposite position; and

FIG. 3 is a rear perspective view thereof.

The element is shaded in FIG. 2 to indicate contrast.

I claim:

The ornamental design for a display element for forming indicia in a sign, as shown and described.
